UNITED STATES PATENT OFFICE.

CHARLES H. HUGHES, OF ENDICOTT, NEW YORK.

TRAFFIC-SIGNAL DEVICE FOR AUTOMOBILES.

Application filed September 2, 1921. Serial No. 487,915.

To all whom it may concern:

Be it known that I, CHARLES H. HUGHES, a citizen of the United States, residing at Endicott, in the county of Broome and State 5 of New York, have invented certain new and useful Improvements in Traffic-Signal Devices for Automobiles, of which the following is a specification.

My invention relates to improvements in traffic signal devices for automobiles, and it has for its object to provide an attractive and distinctive and easily operated traffic signal, by the movements of a human form, which are automatically produced and point 10 the direction of the movements of an automobile to be made, and are especially adapted for the type of cars known as closed cars. And at the same time to produce a distinctive form of device, which will be 15 most likely to attract attention. With these objects in view, my invention consists in certain novel features of construction and arrangement of parts as will be hereinafter more fully described and pointed out in the 20 claims, reference being had to the accompany drawings, in which—

Fig 1 is a front elevation, in perspective of my device.

Fig 2 is a plan view of my device.

Fig 3 is a front elevation in perspective of my device.

Fig. 4 is a perspective view of a detailed part of my device.

The same reference characters denote like parts in each of the several figures of the drawings.

In carrying out my invention, I provide a supporting arm 2, mounted in any convenient manner on the front of the dash A of an automobile and in alinement therewith; a convenient method is by means of bolts or screws 3, 3; on the outer end of the support arm 2, I have the forked extension 4, which may be integral therewith or mounted 45 on the same, by means of bolts or rivets. Through the forked arms 6, 6 of the extension, I have pivotally mounted the vertical rod 7, on which is securely mounted a metallic figure B, representing a human form, and which may be constructed of metal plate or other suitable material; on form B, I have an arm 8 pivotally mounted on the figure. The arm 8 has the pointing hand 9 projecting therefrom. Mounted on 50 rod 7 and between arms 6, 6 of extension 4, I have the crank 10, it being adjustably

mounted on rod 7 by means of the set screw 11, or in any other convenient manner. On the inner end of the support arm 2 and on the outer face thereof, I have the projecting lugs 12, 12, and pivoted between them I have the forked crank 13, and having projecting from the ends of each arm thereof, the lugs 14, 14 and 14', 14'; pivotally mounted between 14' and 14' I have a turn handle 65 rod 15 extending through opening 16 in dash A; between crank 13 and lug 10 I have the rod 17, one end of which is pivotally mounted between lugs 14, 14 and the other end pivotally mounted in lug 10; mounted 70 on the outer end of supporting arm 2, and extending horizontally therefrom, I have the curved forked guide 18 having the divided end formation, consisting of the downward end projection or section 19', projecting into the vertical projection 20, and then projecting back in alinement with the surface of the guide, to the point of spring contact therewith, 26, and in the inner edge of section 19 I have a recess or notch 21; pivotally mounted, in any convenient manner on the lower end of rod 7, but having a vertical pivotal movement, I have the lever 22; between the arm 8 of figure B and lever 22, and having pivotal connection therewith, I 85 have rod 23; mounted on the foot 24 of figure B, I have the coil spring 25 surrounding rod 23, the lower end of spring 25 connecting with lever 22, while the outer end of lever 22 is positioned to rest upon the projected section 19, as shown in Fig. 3; the coil spring 25 is positioned to exert a yielding pressure on lever 22 as it moves around on the projected section 19 and to press the end of lever 22 through recess 21 as the 90 guide 18 is moved backward turned by the movement of the rod 7, and the lever having passed through recess 21 it rests upon the lower curved section 19'; when I pull on handle rod 15 it turns lever 13 and with it draws rod 17 which draws lever 10, which turns rod 7 and with it figure B and also turns lever 22, moving it along the surface of section 19' until it contacts with and raises the end of section 19 forming the 100 opening 26 and through this to the upper surface of guide 18; the lever 22 as it turns raises up or down the rod 23, which in turn raises or lowers the arm 8; when I move the rod 17 forward it turns rod 7, and with it lever 22, which moves upward along the guide 18 and raises rod 23 and with it arm 8 of fig-

ure B, until it reaches a horizontal pointing position, pointing ahead; I can hold it in this position, indicating a forward movement of the automobile; but by moving or turning the figure B farther, the lever 22 reaches recess 21 and drops through it and causes rod 23 to drop and with it arm 8, of figure B. In this position the figure or form B is in alinement with the arm 2; by 10 a further movement of the handle bar 15, the figure B is turned until it assumes a reverse position, and in alinement with the arm 2, as shown in Fig. 1, and the arm 8 is raised pointing to the right, indicating a turn to the right; by again moving forward on the handle lever 15, the lever 22 is moved along guide 18 approaching the recess 21, and the arm 8 is raised pointing to the left, and indicating a turn to the left. 15 20 While the dropped arm 8 indicates that the vehicle is to stop.

Having thus described my invention, what I claim as new and for which I desire Letters Patent is as follows:

25 1. In a traffic signal device for automobiles, a longitudinal arm support mounted on the dash, in alinement therewith and extending beyond the car body, a vertical rod pivotally mounted in the outer end thereof, 30 a metallic human figure vertically mounted on the rod, having one arm pivoted on the shoulder of the figure, a projecting curved guide mounted longitudinally on the outer end of the arm support, said guide having a 35 divided upper surface, the guide projected into upper and lower guide surfaces, with vertical connection between their outer ends, and a spring opening in the upper surface, a forked lever pivoted longitudinally on 40 said support and on the inner end thereof, a handle bar having pivotal connection with one fork of the lever and extending through opening in the dash, a crank removably mounted on the lower end of pivoted end rod, pivotal connection between the 45 forked lever and said crank, a lever mounted on lower end of pivoted end rod, the opposite end of lever adapted to rest on the curved guide, a vertical rod pivotally connected with said lever and the arm of figure, 50 a coil spring surrounding said rod, one end of the spring connected with the figure, and the other with said lever, a recess on the inner edge of the guide surface, means for a 55 longitudinal movement of the turn crank rod, and for positioning the figure and arm, to denote direction.

60 2. A direction signal for automobiles comprising a support extending from the car, a vertical shaft revolvably mounted in the outer end of said support, a sign member secured to the shaft, a direction indicating arm pivoted to the sign member, a projecting curved guide also mounted on the support, a vertically disposed lever connected

to the direction indicating arm at its upper end and with its lower end resting on the curved guide, and means for revolving the vertical shaft and the sign member connected thereto whereby the direction indicating arm will be swung around horizontally 70 with its connecting lever traversing the curved guide.

3. A direction signal for automobiles comprising a support extending from the car, 75 a vertical shaft revolvably mounted in the outer end of said support, a sign member secured to said shaft and revolvable therewith, a direction indicating arm pivoted to the sign member, a projecting curved guide 80 also mounted on the support, said guide provided with a recess, a vertically disposed lever connected to the direction indicating arm and having its lower end resting on the curved guide adapted to enter the recess 85 in the guide, means for revolving the vertical shaft and the sign member connected thereto whereby the direction indicating arm will be swung around horizontally with its connecting lever traversing the curved guide 90 and a spring for projecting the connecting lever into the recess of the guide when in alignment therewith.

4. A direction signal for automobiles comprising a support extending from the car, a 95 shaft revolvably mounted in said support, a direction indicating arm pivotally supported from said shaft, means for revolving said shaft and means for raising and lowering the indicating arm as the shaft revolves. 100

5. A direction signal for automobiles comprising a support extending from the car, a vertical shaft revolvably mounted in the outer end of said support, a sign member secured to said shaft and revolvable therewith, a direction indicating arm pivoted to the sign member, a projecting curved guide also mounted on the support, said guide provided with a major horizontal portion terminating in a downwardly bent portion to 105 provide a depression and then bent upwardly and backwardly to form an arcuate portion disposed in the same plane with the horizontal portion, said arcuate portion being provided with a recess, a vertically disposed lever connected to the direction indicating arm at its upper end and having its lower end resting on the curved guide and adapted to enter the recess therein, 110 means for revolving the vertical shaft and the sign member connected thereto whereby the direction indicating arm will be swung around horizontally with its connecting lever traversing the curved guide and means for projecting the vertically disposed lever 115 downwardly into the recess of the guide when in alinement therewith.

In testimony whereof I have affixed my signature.

CHARLES H. HUGHES.
